[57] CLAIM

The ornamental design for a data processing system, as shown.

DESCRIPTION

FIG. 1 shows our design for a data processing system embodied in a central processor complex shown in perspective from a first side.

FIG. 2 shows the opposite side of the central processor complex of FIG. 1.

FIG. 3 is an end view of the central processor complex looking from the left in FIG. 1 and looking from the right in FIG. 2.

FIG. 4 is a top view of the central processor complex.

FIG. 1
